CARD READER OR SIMILAR ARTICLE

William E. Pascale, San Jose, Calif., assignor to International Business Machines Corporation, New York, N.Y., a corporation of New York

Filed Aug. 31, 1964, Ser. No. 81,533

Term of patent 14 years

(Cl. D26—5)

FIG. 2

FIG. 3

FIG. 1 is a front perspective view of a card reader or similar article showing my new design;

FIG. 2 is a top plan view thereof; and

FIG. 3 is a right side elevational view thereof.

The rear of the machine, not shown, is substantially plain and unornamented.

The fragmentary, broken line showing of a support cabinet in FIGS. 1 and 3 is for illustrative purposes only.

I claim:

The ornamental design for a card reader or similar article, as shown and described.
